UNITED STATES PATENT OFFICE.

EDMUND ROSENBERG, OF INDIANAPOLIS, INDIANA.

GEARING FOR AWNINGS.

No. 905,002.

Specification of Letters Patent.

Patented Nov. 24, 1908.

Application filed December 31, 1907. Serial No. 408,852.

To all whom it may concern:

Be it known that I, EDMUND ROSENBERG, a citizen of the United States, residing at Indianapolis, in the county of Marion and

5 State of Indiana, have invented certain new and useful Improvements in Gearing for Awnings; and I do declare the following to be a full, clear, and exact description of the invention, reference being had to the accompanying drawings, and to the letters and figures of reference marked thereon, which form a part of this specification.

This invention relates to awnings, especially to the class of awnings that are of 15 relatively large size that are designed to be used on the walls of buildings such as the fronts of mercantile houses or factories, the invention having reference particularly to gearing for operating the awnings so that 20 they may be either rolled up or unrolled at pleasure.

Objects of the invention are to provide improved gearing for roller awnings that will be adapted for universal application 25 and permit of the different parts being mounted cheaply against buildings; and to provide gearing that may not only be quickly adjusted to the walls of the buildings, but which will be relatively light in weight and 30 be strong, durable and economical in use.

The invention comprises certain novel features relating to the awning roller and the housing thereof and also a crank-box and connections between the crank-box and 35 the roller, the invention consisting further in the parts and combinations and arrangements of parts as hereinafter particularly described and defined in the appended claims.

Referring to the drawings Figure 1 is a 40 fragmentary front elevation of an awning and gearing constructed substantially in accordance with the invention; Fig. 2, a vertical sectional view approximately on the line A A in Fig. 1; Fig. 3, an end view of 45 the awning roller; Fig. 4, a sectional view of a portion of the roller approximately on the line B in Fig. 3; Fig. 5, a front view of a gear wheel for operating the roller; Fig. 6, an end view of the socket connection of the 50 gear wheel; Fig. 7, a perspective view showing an end part of the drive shaft of the gear wheel shown in Fig. 5; Fig. 8, a front view of the crank-box without its cover or front; Fig. 9, a front view of the base of 55 the crank-box; Fig. 10, a perspective view of the housing of the roller gearing; Fig. 11,

a perspective view of one of the wall parts of the crank-box; and, Fig. 12, a perspective view of the other one of the two wall parts of the crank-box. 60

Similar reference characters in the various figures of the drawings designate like elements or features of construction.

In Figs. 1 and 2, the numeral 1 designates a foundation board or part of a building, 65 and 2 another foundation board or a building wall for supporting the awning roller and gearing; 3, designating the body of the awning roller, and 4 the awning composed of canvas or other suitable material. The 70 body of the roller is preferably composed of wood and has metallic sockets 5 and 6 on its ends for rotatively supporting the roller, one socket being provided with a journal 7 mounted in a bearing 8 that is attached to 75 the member 2. Each socket preferably has a slot 9 therein through which the fabric awning extends to the body of the roller to which it is suitably attached, so that the awning may have the maximum width between the bearings of the roller, the socket 5 being provided with a journal 10 for its support.

A housing for one end of the roller comprises a plate 11 having bolt holes 11' and 85 adapted to be bolted against the wall of the building, the housing having a journal bearing 12 supporting the journal 10 and provided with a cap 13. The socket 5 has a squared part 14 adjacent to the journal 10 and has a 90 gear wheel 15 mounted thereon, said wheel having spherically shaped teeth 16 connected by a ring 17 that extends about the extremities of the teeth and serves to strengthen them, and also to prevent the edge of the 95 awning when being rolled up from being drawn into the teeth. The housing comprises also a bearing 18 connected by plates 19 and 20 to the bearing 12 and provided with a cap 21, there being a bearing 22 in 100 alignment with the bearing 18, and provided with a cap 23 adjacent to the bearing 12. A socket 24 has its exterior journaled in the bearing 18 and its cap 21 and has a flange 25 engaging the upper side of the bearing and 105 its cap, the socket having a short spindle 26 journaled in the bearing 22 and its cap 23, there being a lug 27 on the body of the socket 24 in engagement with a wheel hub 28 having gear teeth 29 on the spindle 26, the teeth 29 being in engagement with the gear teeth 16. The socket 24 has four recesses 30, 31,

32, 33 therein, and serves as a part of a universal coupling for driving the awning roller by means of the two gear wheels above-described.

5 An improved crank box comprises a base 34 having bolt holes 34' and having also a flange 35 at the front thereof, the base being adapted to be bolted against the front of the building at a suitable distance below the awning roller, so as to be within reach of a person on the ground. The body or walls of the crank-box comprise two principal parts, the upper wall 36 having two side wall parts 37 and 38 formed integrally therewith, the 15 wall 36 having a journal bearing 39 therein, the other principal part comprising a lower wall 40 having two side wall parts 41 and 42 formed integrally therewith and adapted to abut the wall parts 37 and 38, said wall parts 20 fitting closely against the inner side of the flange 35. The wall 40 has a journal bearing 43 formed on the inner side thereof, and has a suitable member in which is a shaft-guide 44. The crank-box has a front or cap 25 45 suitably bolted against the body walls and holding them securely against the base 34. A bevel gear wheel 46 is suitably journaled in the bearing 39 and has a socket 47 therein formed like the interior of the socket 24 30 above-described and shown in Fig. 6. A rotative shaft 48 of suitable length has suitably attached end parts 49 and 50, each end part having four lateral projections 51, 52, 53, 54 inserted in either socket 24 or 47, and 35 permitting the shaft to be arranged at different angles to the perpendicular or axes of the rotative members that are mounted in the bearings 18 and 39. A bevel gear wheel 55 has a journal 56 mounted in the front 45 and 40 engages the wheel 46, the inner side of the wheel 55 being guided laterally by the guide 44, and against the side of the bearing 43, the lower side of the wheel 46 being guided in the bearing 43. The shaft of the wheel 55 45 has a squared part 57 and a squared terminal end 58 adapted to receive a crank arm for operating the gearing. A sliding gravity latch bolt 59 is mounted in guideways 60 and 61 of the upper and lower walls 50 respectively of the crank-box, and has an opening 62, the sides of which are adapted to engage the squared part 56 to prevent rotation thereof when the latch bolt is in its normal lowermost position, there being an enlarged 55 part 62' of the opening adapted to permit rotation of the squared part 56 when the latch is elevated.

In practical use, in many cases it is desirable and may be necessary to place the crank-box in an arbitrary position with respect to the awning roller, the distances between the two being in some cases greater or less than in others, and after the roller has been suitably mounted in a desired position and a 60 65 crank box attached to the building, measure-

ments may be taken and the shaft 48 may then be cut to the desired length, so as to be connected to the end parts 49 and 50. Normally the latch bolt 59 will prevent operation of the gearing and must be elevated and 70 so held while operating the gearing, either to elevate or to lower the awning. In operating the gearing any suitable crank arm or wrench may be applied to the squared end 58 which projects beyond the front 45 of the 75 crank box, so as to rotate the shaft 48 and consequently rotate the awning roller in a desired direction. It will be understood from a description of the mechanism, that in most cases the awning will not descend of its 80 own accord and turn its gearing, so that accidents from such cause are not liable to happen, it usually being necessary to manually operate the gearing.

Having thus described the invention, what 85 is claimed as new is—

1. Awning gearing including a crank-box, a gear wheel journaled in the crank-box and having a socket therein that has a plurality of recesses in the inner side of the wall thereof, a gear wheel journaled in the crank-box and engaging the gear wheel that has said socket therein, and a drive shaft having an end part connected thereto provided with a plurality of lateral projections, the end part 95 extending into said socket with the projections thereof in said recesses.

2. Awning gearing including a housing, a socket having a journal that is mounted rotatively in the housing, said socket having a 100 squared part adjacent to said journal, a roller secured in said socket, a gear wheel on said squared part and having spherically-shaped teeth, a ring formed integrally on the extremities of said teeth, a spindle journaled in 105 the housing, a toothed wheel on the spindle engaging said spherically-shaped teeth, and a drive shaft coupled to said spindle.

3. Awning gearing including a housing having a journal bearing, a roller journaled 110 in the housing, a toothed gear wheel attached to the roller, a socket having a spindle and journaled in the journal bearing and having a flange that bears on the top of the bearing member, the socket having a plurality of recesses in the inner side of the wall thereof, a toothed wheel on the spindle in engagement with the teeth of the gear wheel above-described, and a drive shaft having a plurality 115 of lateral projections entered in the recesses 120 of the socket.

4. Awning gearing including a crank box comprising a base having a flange, two body parts on the base engaging the flange and having each a journal bearing therein and also a guideway in the forward edge thereof, a front or cap secured against the forward edges of the body parts, a toothed wheel mounted in the journal bearings of the body parts, a toothed wheel journaled in 125

the front or cap and engaging the first-described wheel and having a squared part, a movable latch bolt mounted in the guideways of the body parts and having an opening therein the sides of which may engage said squared part, and a shaft connected with said first-described wheel.

5. In awning gearing, the combination of a housing comprising a base member, a horizontal bearing having a cap, a vertical journal bearing having a cap, two plates connecting the horizontal bearing and the vertical bearing, and a relatively small vertical journal bearing adjacent to the horizontal journal bearing, with a roller journaled in the horizontal bearing, a toothed wheel on the roller, a socket journaled in the first-described vertical bearing and having a spindle journaled in the small vertical bearing, and

20 a toothed wheel on the spindle engaging the toothed wheel first-described.

6. In awning gearing, the combination of a stationary housing, a roller journaled in the housing, a gear wheel secured to the roller, a socket journaled in the housing and having a plurality of recesses in the inner side of the wall thereof, a gear wheel connected with said socket and engaging said first-mentioned gear wheel, a stationary 25

30 crank-box remote from the housing, a gear wheel journaled in the crank-box and having a socket therein that has a plurality of recesses in the inner side of the wall thereof, a

gear wheel journaled in said crank-box and engaging said gear wheel that has said socket 35 therein, and a drive-shaft having two end parts connected thereto provided each with a plurality of lateral projections, one of said end parts extending into said socket that is journaled in the housing with the projections thereof in the recesses of the socket, and the other one of the end parts extending into the socket of said gear wheel with the projections thereof in said recesses of the socket.

7. In awning gearing, the combination of a socket having a journal on the outer side of the wall thereof, and having also a plurality of recesses in the inner side of said wall, and a toothed wheel connected fixedly 50 with said socket.

8. In awning gearing, a drive shaft having an end part connected thereto that has a plurality of projections thereon, in combination with a journal-bearing, a socket journaled 55 in said journal-bearing and having a plurality of recesses in the inner side of the wall thereof receiving said projections, and a toothed wheel connected fixedly with said socket.

In testimony whereof, I affix my signature in presence of two witnesses.

EDMUND ROSENBERG.
